UNITED STATES PATENT OFFICE

2,567,489

HAND BANDAGE

Douglas T. Lewis, Los Angeles, Calif.

Application February 21, 1949, Serial No. 77,625

8 Claims. (Cl. 2—20)

1

This invention relates to new and useful improvements and structural refinements in hand protectors for boxers, fighters, and the like, and the principal object of the invention is to protect the hands of such persons against bruising or other injuries.

This object is achieved by the provision of what may be referred to as a hand bandage formed from resilient material and adapted to cover the carpus, metacarpus and portions of phalanges of the hand, and an important feature of the invention resides in the provision of means for securely but removably fastening the bandage in proper position, so that it does not become displaced and rendered ineffective while in use.

Some of the advantages of the invention lie in its simplicity of construction and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view showing the invention in situ on a hand;

Figure 2 is an underside perspective view of the subject illustrated in Figure 1;

Figure 3 is an undersize perspective view of the invention per se, the same being shown untied;

Figure 4 is a top perspective view of the subject shown in Figure 3, and

Figure 5 is a fragmentary perspective detail, taken substantially in the plane of the line 5—5 in Figure 3.

Like characters of reference are employed to designate like parts in the specification and throughout the several views.

Referring now to the accompanying drawings in detail, the invention consists of a hand bandage designated generally by the reference character 10, the same preferably being formed almost in its entirety from resilient material such as elastic fabric of the "two way stretch" type, the bandage comprising a glove-shaped body 12 which is adapted to receive therein the metacarpus of a hand and is provided at one end with a sleeve-like extension 14 to receive the carpus.

The relatively opposite end portion of the body 12 is formed with a set of open-ended, tubular members 16 to receive inner portions of the

2

phalanges, while the thumb which is also included among the phalanges is partially receivable in a similar, open-ended and tubular member designated by the separate reference character 18. The member 18 is, of course, disposed at one side of the body 12, and it is to be noted that when the bandage is applied to the hand, the several fingers project outwardly through the open ends of the members 16, 18, as will be clearly apparent.

For purposes of reinforcement, a covering sheet 20 may be secured by sewing to the top portion of the body 12 as well as the top portions of the members 16, the lateral edges of this sheet extending partly around the sides of the body 12, as is best shown in Figure 3. It is to be also noted that the open ends of the members 16, 18 as well as the open end of the extension 14 may be reinforced with suitable hems 20, 22, 24 respectively, containing elastic bands, as is typified at 26 in Figure 5.

This arrangement will not only substantially reinforce the open end portions of the members and extension, but it will also assist in assuring a tight fit of the bandage on the hand, as will be clearly apparent.

However, additional means are provided for firmly yet removably retaining the bandage in situ on a hand, these means consisting of a strap 28 which may either be provided with a relatively wide intermediate portion 30 secured by stitching to the aforementioned covering sheet 20, or wherein the covering sheet itself may constitute an integral, intermediate portion of the strap.

In any event, the end portions 32, 34 of this strap extend laterally to both sides of the body 12 and are windable in relatively opposite directions around the body and around the extension 14. To this end, the strap portion 32 may be formed with an elongated opening 36 in which the thumb member 18 may be received while the strap portions 32, 34 are being wound, and it is to be noted that the ends of the strap portions 32, 34 are equipped with hook-shaped fasteners 38 which are engageable selectively with a plurality of coacting eyelets 40 provided on the underside of the extension 14. In this manner, after the strap portions 32, 34 are tied and secured, the entire bandage will be firmly retained in position on the hand, and accidental or unintentional displacement thereof will be prevented.

In the interest of additional protection, the fasteners 38 may be provided on the outside

thereof with suitable protecting pads 42, as will be clearly apparent.

It is believed that the advantages and use of the invention will be readily understood from the foregoing disclosure and accordingly, further description thereof at this point is deemed unnecessary.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

1. In a hand bandage, the combination of a glove-shaped body formed from resilient material and adapted to cover the metacarpus of a hand, a sleeve-like carpus receiving extension 20 provided on said body, said body including a set of open-ended tubular members adapted to receive therein inner portions of the phalanges, a strap having an enlarged intermediate portion secured to said body and the end portions thereof tapering and extending laterally and oppositely from the intermediate portion, the end portions of said strap being windable in opposite directions around said body and said extension, one of said end portions being formed with an opening receiving one of said members when said end portions are wound around said body, fastening elements provided at the ends of said strap, and coacting fasteners on said extension, whereby the ends of said strap may be releasably secured.

2. The device as defined in claim 1 together with protector pads provided on said first mentioned fastening elements.

3. A hand protector comprising a flexible body having finger stalls formed at one end thereof, said body having laterally and oppositely extending portions which are tapered substantially throughout their entire length and provided with means at their outer ends for being secured to each other upon being oppositely wound about 45 the metacarpus and carpus of the wearer.

4. A hand protector comprising a flexible body having finger stalls formed at one end thereof, said body having laterally and oppositely extending portions which are tapered substantially throughout their entire length and provided with means at their outer ends for being secured to each other upon being oppositely wound about the metacarpus and carpus of the wearer, one of said laterally extending portions being provided intermediate its ends with an opening for receiving the thumb of the wearer therethrough.

5. As a new article of manufacture, a flexible glove-like body having openings provided there-

in for the extension of the phalanges of the wearer therethrough, laterally and oppositely extending flexible members secured to said body both of which are tapered substantially throughout their entire length and provided at their extremities with means for being secured to each other upon being oppositely wound about the hand of the wearer.

6. As a new article of manufacture, a flexible glove-like body having openings provided therein for the extension of the phalanges of the wearer therethrough, laterally and oppositely extending flexible members secured to said body both of which are tapered substantially throughout their entire length and provided at their extremities with means for being secured to each other upon being oppositely wound about the hand of the wearer, one of said members being provided with an opening that is in registry with one of the aforementioned openings upon being wound about the hand of the wearer, whereby the thumb of the wearer may extend therethrough.

7. As a new article of manufacture, a flexible and padded glove-like body having openings provided therein for the extension of the phalanges of the wearer therethrough, laterally and oppositely extending flexible members secured to said body both of which are tapered substantially throughout their entire length and provided at their extremities with means for being secured to each other upon being oppositely wound about the hand of the wearer.

8. A hand protector comprising a flexible glove-like body including a tubular portion for the reception of a thumb of the wearer, laterally and oppositely extending straps carried by said body that are tapered substantially throughout their entire length and which are provided with means for securing the same upon being oppositely wound about the metacarpus and carpus of the wearer, one of said straps being provided intermediate its ends with an opening receiving said tubular portion when the strap is wound about the wearer.
